DISPENSING ATTACHMENT FOR COLLAPSIBLE TUBES

Charles Stewart Mann, Vancouver, British Columbia, Canada

Application September 13, 1937, Serial No. 163,566

6 Claims. (Cl. 221—60)

My invention relates to improvements in dispensing attachments for collapsible tubes which are particularly adapted for use in dispensing cosmetics, face cream and the like, where the 5 paste or cream expressed from the tube is to be wiped off with the finger tip. Also to provide a structure of such shape which can be left perfectly clean and sanitary without effort by the simple expedient of severing the ribbon of paste 10 from the tube. Further objects are to provide a spring structure for closing the attachment which will afford a relatively long closing movement in an attachment which is desirably short in design.

15 The invention contemplates a structure requiring a complete turn of the cap to open and a novel method of securing the attachment to the nipple of a collapsible tube which will be fully described and shown in the accompanying drawing, in which:

Fig. 1 is a vertical sectional view of the invention.

Fig. 2 is a sectional view of the plunger showing the preferred type of bolt spring.

25 In the drawing like characters of reference indicate corresponding parts in each figure.

The numeral 1 indicates a collapsible tube of the usual type having shoulders 2 and a nipple 3 through which the contents of the tube are normally expressed. Fitted upon the nipple is an internally threaded sleeve 4 having a conical flange 5 which is provided on its under face with an annular recess 6 for the purpose of bridging over any lettering which may be embossed upon 30 the shoulders of the tube and to permit said flange to contact intimately the shoulders of the tube.

A flange 7 extends inwardly of the threaded sleeve 4 which bears down upon a packing washer 8. The sleeve 4 is provided with an external packing ring 9 and an annular groove 10, the purpose of which will hereinafter appear.

40 Mounted upon the threaded sleeve 4 is an inner sleeve 11 which is supported upon the sleeve 4 by radial arms 12 secured in position by any suitable means. The inner sleeve 11 is provided with a vertical slot 13 in its side wall which non-rotatably guides a plunger 14 slidably mounted therein.

45 Rotatably mounted upon the threaded sleeve 4 is a collar 15 surmounted by a cap 16, which cap is substantially ovaliform in cross section to facilitate thorough cleansing after use by the simple expedient of wiping off the cream extruded 50 from the tube with the finger tip. The collar 15

and its cap are held against endwise movement by a grub screw 17 entering into and engaging the annular groove 10. The cap is provided with a discharge orifice 18 which is adapted to be closed by the endwise movable plunger 14 fitted 5 in the inner sleeve 11.

The plunger 14 is provided at its base with a stem 20 surrounded by a compression spring 21, which latter abuts the bottom wall of a spring well 22 fitted into the base of the inner sleeve 11. 10 A bolt 23 is retractably carried by the plunger 14, which is adapted to engage a spiral slot 24 formed in the inner peripheral wall of the cap 16. This spiral slot extends one complete turn and terminates in an upper slot terminal 25 and a 15 lower slot terminal 26, which are aligned with each other parallel to the vertical axis of the tube. The upper slot terminal 25 is bevelled on its under side to facilitate the entry of the bolt 23.

The bolt 23 is slidably mounted in a socket 27, 20 see Figure 2, which socket is screwed into the plunger 14. An axial recess 28 is formed in the socket 27 and a complementary recess 29 is formed in the bolt 23 and in these two recesses a compression spring 30 is housed which urges 25 the bolt radially outwards through the vertical slot 13.

A thumb button 31 having a stem 32 is slidably mounted in the cap 16 and is urged in an outward direction by a spring 33. The stem 32 is 30 surrounded by a packing ring 32A which is compressed in the usual way by a gland collar 32B. The inner end of the stem enters the lower slot terminal 26 and has sufficient sliding movement to thrust the bolt 23 clear of said terminal. 35

The threaded sleeve 4 is non-rotatably secured to the nipple 3 by a pointed pin 34 having a head 35 under which a spring 36 is placed to urge the pin outwardly.

A threaded opening 37 is formed in the collar 40 15 which is adapted to be brought into register with the pin 34, and a screw plug 38 is fitted into said opening, which is of such length that its inner face coincides with that of the inner face of the collar, so that the cap may be turned 45 about the threaded sleeve without affecting the position of the pin 34.

When cream has been dispensed through the orifice 18 pressure applied to the press button 31 will release the bolt 23 from the spiral slot 24 50 leaving it engaged only in the vertical slot 13 of the inner sleeve 11; the spring 21 then urges the plunger upwardly to close the discharge orifice and permit the bolt 23 to enter the upper slot terminal 25 of the slot 24. To open the discharge 55

orifice again, it suffices to rotate the cap 16, causing the bolt 23 to be urged downwardly along the spiral slot 24 and the vertical slot 13 and bring the plunger downwardly to the position shown, 5 when the bolt 23 will again be aligned with the stem 32 of the press button 31.

It will be obvious that the extrusion of paste will be automatically shut off, the orifice closed and hermetically sealed in response to the application of pressure to the thumb button. 10

What I claim as my invention is:

1. In a dispensing attachment having an internally threaded sleeve adapted for attachment to the nipple of a collapsible tube, a cap having a 15 collar rotatable about the sleeve, said sleeve having an opening through its wall, a pin in said opening adapted to project into the nipple of the tube, said collar having a threaded opening and a screw plug therefor adapted to be brought into 20 register with the opening in the sleeve, said screw plug when seated in its threaded opening being adapted to press the pin into the nipple and to project to the inner peripheral face of the collar to permit the cap to rotate freely about the sleeve 25 while retaining the pin projected into the nipple of the tube.

2. In a dispensing attachment having an internally threaded sleeve adapted for attachment to the nipple of a collapsible tube, a cap having a 30 collar rotatable about the sleeve, said sleeve having an opening through its wall, a pin in said opening adapted to project into the nipple of the tube, said collar having a threaded opening and a screw plug therefor adapted to be brought 35 into register with the opening in the sleeve, said screw plug when seated in its threaded opening being adapted to press the pin into the nipple and to project to the inner peripheral face of the cylindrical portion to permit the cap to rotate 40 freely about the sleeve, said pin having an enlargement at its inner end and a spring to urge it outwardly from its position of engagement with the nipple.

3. A dispensing attachment for collapsible 45 tubes comprising a sleeve adapted for attachment to the nipple of said tube, a cap rotatable about the sleeve, said cap having a discharge orifice adjacent its upper end, a press button upon its outer periphery and a spiral slot formed in its

inner periphery, an inner sleeve carried by the first mentioned sleeve, said inner sleeve having a vertical slot, a plunger slideable within the inner sleeve adapted to close the discharge opening, a bolt projectable from the plunger through the vertical slot and into the spiral slot, said press button being aligned in the cap to disengage the bolt from the spiral slot when said bolt is at the lower terminal portion of said spiral slot, and means for moving the plunger to close the discharge orifice. 5 10

4. A dispensing attachment for collapsible tubes comprising a sleeve, a cap rotatable about the sleeve having a spiral groove upon its inner periphery and a discharge orifice, a non-rotating plunger for closing the orifice, a spring projected bolt carried by the plunger normally engaging the spiral groove of the cap, means accessible through the wall of the cap for thrusting the bolt out of the spiral groove, and spring means for moving 20 the plunger to close the orifice. 15

5. A dispensing attachment for collapsible tubes comprising a sleeve, a cap rotatable about the sleeve having a spiral groove upon its inner periphery and a discharge orifice, a non-rotating plunger for closing the orifice, a spring projected bolt carried by the plunger normally engaging the spiral groove of the cap, means accessible through the wall of the cap for thrusting the bolt out of the spiral groove, and spring means for 25 moving the plunger to close the orifice, said cap having an ovaliform cross section with its major axis extending through the longitudinal axis of the plunger. 30

6. A dispensing attachment for collapsible tubes comprising a sleeve, a cap rotatable about the sleeve having a spiral groove upon its inner periphery and a discharge orifice, a plunger for closing the orifice, a non-rotating sleeve surrounding the plunger, said sleeve having a vertical slot, a spring projected bolt carried by the plunger extending through the vertical slot and normally engaging the spiral groove of the cap, means accessible through the wall of the cap for thrusting the plunger out of the spiral groove, 40 and spring means for moving the plunger to close the orifice. 45
